STOP MECHANISM FOR KNITTING MACHINES

Michael Wachsman, Brooklyn, N. Y.

Application May 19, 1937, Serial No. 143,407

5 Claims. (Cl. 66—163)

This invention relates to improvements in stop mechanisms for knitting machines of the type shown in Reissue Patent 19,069, February 6, 1934. The stop mechanism disclosed in said patent includes a supporting box in which there is pivoted a knot detector lever and an end detector lever both of which support the thread from the bobbins. When a knot occurs the knot detector lever is pulled down and makes an electrical contact inside the box whereby to close an electrical circuit which in turn operates the stop mechanism of a knitting machine. When the thread breaks or runs out, the end detector lever rises by gravity and likewise serves to close the electrical circuit. Inside the box are electrical contact springs and the said two levers have contact heel which engage the said springs to close the circuit. This type of stop mechanism is well known in the art.

Heretofore the contact springs have been in the form of leaf springs which are not easy to adjust and which become readily bent out of shape by continued use. Furthermore, being leaf springs anchored at one end they cannot readily be adjusted to such a fine degree as is required to space the free ends from the contact heels on the detector levers. There is another disadvantage in that the contact closing mechanism is enclosed within the box and it is therefore not possible to check any change in the positions of the contact springs which may be caused by wear or by vibration or for other reasons.

The object of my invention is to provide an improved contact mechanism to be used within the box of a device such as described and disclosed in the said patent and other patents. Specifically the object of my invention is to employ spring actuated levers in place of contact springs and to shape such levers so that they may be more easily and smoothly engaged by the contact heels. This makes for a more positive and precise operation. Other objects of my invention are to provide certain improvements which will be pointed out hereinafter and which serve chiefly the purpose of more efficient operation.

Accordingly my invention is embodied in a stop mechanism for knitting machines arranged and constructed as hereinafter set forth and as illustrated in the accompanying drawing in which

Fig. 1 is a sectional view of the stop mechanism with parts removed and parts broken away.

Fig. 2 is a face view of the contacting levers which are engaged by the contact heels.

Fig. 3 is a horizontal detailed view showing the arrangement of the knot detector lever and the

end detector lever with relation to the box, parts being in section and parts broken away.

Fig. 4 is a sectional view showing a modified construction of the contact heel on the knot detector lever, parts being in section and parts broken away.

Fig. 5 is a plan view of the modified contact heel shown in Fig. 4.

Fig. 6 is a view partly in section and with parts removed showing a modified construction of the contact heel on the end detector lever.

In the drawing the contacting mechanism is contained within a suitably formed box 1 having side walls 2 in which there is pivoted at 3 a gravity actuated end detector lever 4 which extend forwardly from the box, Figs. 1 and 3, and which is caused to rise by means of a weight 5. At 6 there is pivoted a knot detector lever 7 which has two forwardly extending porcelain arms 8 one on each side of the end detector lever 4. The lever 7 is held in its upper normal position against stops 9 formed in the front of the box by a spring 10 attached to a keeper 11 which moves between the side walls of the box and is adjustable by a screw 12 whereby to adjust the tension of the spring 10.

This arrangement is disclosed in prior patents. It has been found, however, that because of vibration by the knitting machine the keeper 11 does not remain in adjusted position upon the screw 12. I therefore propose to provide a spring 13 attached to the keeper and to the box. The spring exerts a steady pull on the keeper and prevents looseness between the keeper and the screw. Of course, when the keeper is moved up or down to adjust the spring 10, the spring 13 will be stretched accordingly as will be understood. The spring 10 is attached to the contact heel 14 of the knot detector lever. Similarly the end detector lever has a contact heel 15.

It is desirable that the contact making mechanism to be used in the box be so arranged that it may be assembled as a unit and thereafter attached without requiring any special tools or special effort. In the present instance this mechanism is embodied in a contact plate 16 in which there is pivoted at 17 and 18 respectively an upper and a lower contact lever 19 and 20. The upper lever has a stop 23 and a contacting arm 21 which ends in a hook 22. The lower lever 20 is formed with a contacting arm or portion 24 and is also provided with a stop 25. A spring 26 is attached to the two levers as shown and serves to keep them in contact making positions, the stops 23 and 25 engaging the contact plate for this purpose as shown and as will be understood.

5 The contact plate with its levers is mounted in the box 1 before the cover 27 is attached and the attaching means may be a screw 28 and a bolt 29 which pass through the back of the box and whereby the plate is accurately positioned with respect to the two contact heels 14 and 15. The contact plate is suitably insulated from the box as indicated at 30. The bolt 29 serves as a fixed circuit terminal in a manner well understood in the art, the circuit being indicated by 10 the wire 31.

15 The normal positions of the parts are as shown in Fig. 1. If a knot occurs on the thread 32, both levers will be pulled down. The contact heel 14 therefore rises and engages the contact portion 24 of the lever 20 with an easy wiping movement and thereby closes the circuit, the operation being well known in the art. When the thread breaks or runs out, the end detector lever will 20 rise and its contact heel 15 will engage the contacting arm 21 with an easy wiping movement.

25 The rising movement of the lever 4 will be stopped by the hook 22. This occurs when the lever 4 reaches the dotted position at 33. The contact lever 19 therefore serves a two-fold purpose in that it closes the circuit by contacting the end detector lever and also stops the end detector lever in its upward swinging movement so that it is not necessary to provide the end detector 30 lever with a special bend or like means to insure that the lever does not swing too far.

35 Fig. 4 illustrates a modification in which the knot detector lever 7 is provided with a contact shoe 35 which, when the lever is pulled down by the thread, engages the contact arm 36 of the contact lever 37 pivoted at 38 on the contact plate 16. In this instance the contact lever is held in its upper predetermined position by a spring 39 which is coiled around the pivot 38. 40 With a construction as in Fig. 4 the knot detector lever will likewise be kept in position by an individual coiled spring. This is not shown because it is a duplicate of the spring 39, the construction being the same.

45 It may not always be desirable to have an outside weight as 5 in Fig. 1. Fig. 6 therefore illustrates a modification in which the detector lever 4 is provided with a counterweight 40 within the box. The counterweight is adapted to engage the upper contact lever 19 as will be understood. The weight is attached to the lever 4 by a set screw 41 which also serves to attach the upper end of a spring 42 the tension of which is adjustable by a screw 43. The construction is 50 Fig. 6 includes the advantage of a very fine adjustment of the end detector lever by the spring 42.

I claim:—

1. In a stop mechanism of the character described, a housing, an upper and a lower thread supporting lever pivoted on said housing, each of said levers having a contact heel extending within the housing, a contact plate in the housing, an upper and a lower contact arm pivoted on the contact plate and adapted respectively to be

engaged by the contact heels of the said upper and lower thread supporting levers and means including a fixed electric circuit terminal for supporting the contact plate in the housing to position the contact arms in operative relation to the said contact heels. 5

2. In a stop mechanism of the character described, a housing, an upper and a lower thread supporting lever pivoted on said housing, each of said levers having a contact heel extending within the housing, a contact plate, an upper and a lower contact arm pivoted on said plate, spring means secured to the contact arms for keeping the same in predetermined position with respect to said contact plate and to permit movement of 10 said arms with respect to the plate, means for securing the latter within the housing with the said contact arms in relative predetermined operative positions with respect to the heels of the said thread supporting levers. 20

3. In a stop mechanism of the character described, a housing, an upper and a lower thread supporting lever pivoted on said housing, each of said levers having a contact heel extending within the housing, springs secured to said contact heels to maintain said levers in predetermined fixed positions within the housing, a contact plate, an upper and a lower contact arm pivoted on said plate and adapted to swing with relation to the plate, a spring connecting said contact arms to maintain the latter in predetermined fixed positions with relation to the plate and electric connecting means for connecting the contact plate to the housing. 25

4. In a stop mechanism of the character described, a housing, an upper and a lower contact lever pivoted on the housing, each of said levers having a contact heel extending within the housing, a contact plate, an upper contact arm pivoted on said plate, a stop on said contact arm adapted to be engaged by the upper contact heel, a lower contact arm pivoted on said plate and adapted to be engaged by the lower contact heel, spring means connected to said contact arms to maintain the same in predetermined yielding 40 positions with respect to the said contact heels and means for securing the contact plate to the housing. 45

5. In a stop mechanism of the character described, a housing, an upper and a lower contact lever pivoted on the housing, each of said levers having a contact heel extending within the housing, a separate weight forming the contact heel on one of said levers, a contact plate, an upper contact arm pivoted on said plate, a stop on said contact arm adapted to be engaged by the upper contact heel, a lower contact arm pivoted on said plate and adapted to be engaged by the lower contact heel, spring means connected to said contact arms to maintain the same in predetermined yielding 55 positions with respect to the said contact heels and means for securing the contact plate to the housing. 60
